Primary Examiner—Brian N. Vinson(74) *Attorney, Agent, or Firm*—Gifford, Krass, Groh, Sprinkle, Anderson & Citkowski, P.C.(57) **CLAIM**

I claim the ornamental design for a merchandising display structure, as shown and described.

DESCRIPTION

FIG. 1 is a top, front, and left side perspective view of a

merchandising display structure showing a first embodiment of my new design;

FIG. 2 is a top plan view thereof;

FIG. 3 is a front elevational view thereof;

FIG. 4 is a bottom plan view thereof;

FIG. 5 is a left side elevational view thereof;

FIG. 6 is a right side elevational view thereof;

FIG. 7 is a fragmentary top, front, and left side perspective view of a merchandising display structure showing a second embodiment of my new design, with the horizontal and vertical elements omitted for convenience of illustration, and the only difference from the other embodiments residing in the appearance of the portion shown;

FIG. 8 is a fragmentary top, rear, and right side perspective view thereof;

FIG. 9 is a fragmentary top, front, and left side perspective view of a merchandising display structure showing a third embodiment of my new design, with the horizontal and vertical elements omitted for convenience of illustration, and the only difference from the other embodiments residing in the appearance of the portion shown;

FIG. 10 is a fragmentary top, rear, and right side perspective view thereof;

FIG. 11 is a fragmentary top, front, and left side perspective view of a merchandising display structure showing a fourth embodiment of my new design, with the horizontal and vertical elements omitted for convenience of illustration, and the only difference from the other embodiments residing in the appearance of the portion shown;

FIG. 12 is a fragmentary top, rear, and right side perspective view thereof;

FIG. 13 is a fragmentary top, front, and left side perspective view of a merchandising display structure showing a fifth embodiment of my new design, with the horizontal and vertical elements omitted for convenience of illustration, and the only difference from the other embodiments residing in the appearance of the portion shown; and,

FIG. 14 is a fragmentary top, rear, and right side perspective view thereof.
